C. F. HOOFER,
WHEEL FLANGE OIL DISTRIBUTER.
APPLICATION FILED FEB. 5, 1918.

Patented Sept. 17, 1918.

1,279,345.

Charles Frederick Kooper

UNITED STATES PATENT OFFICE.

CHARLES F. HOOFER, OF SEATTLE, WASHINGTON, ASSIGNOR TO HOOFER MANUFACTURING COMPANY, A CORPORATION OF WASHINGTON.

WHEEL-FLANGE OIL-DISTRIBUTER.

1,279,345.

Specification of Letters Patent. Patented Sept. 17, 1918.

Application filed February 5, 1918. Serial No. 215,477.

To all whom it may concern:

Be it known that I, CHARLES FREDERICK HOOFER, a citizen of the United States, and a resident of the city of Seattle, in the county of King and the State of Washington, United States of America, have invented new and useful Improvements in Wheel-Flange Oil-Distributors for Lubricating the Flanges of Track-Vehicle Wheels, of which the following is a specification.

This invention relates to wheel flange Lubricators of the type disclosed in my companion application Serial No. 171,566, dated May 28, 1917, the object of my present invention being to provide a simple, reliable and inexpensive device, and it consists in the constructions, combinations and arrangements herein described and claimed.

Another object of my invention is to provide an oil distributor shoe, having an end adapted to fit over a wheel flange, and having a longitudinal cavity therein which provides a source of least resistance which the normal wearing action of a revolving wheel flange will follow.

A further object of my invention is to provide means for equalizing the normal wear within the discharge end of the oil distributor shoe, and to that end I have designed a hollow distributor shoe, having walls of such relative proportions to each other, that the walls on either side of the wheel flange will feed-up fresh material, thereby compensating for lateral wear on their inner surfaces.

A still further object of my invention is to provide a detachable distributor shoe, of simple construction, and conveniently arranged for renewing the same as needed.

Other objects and advantages will appear in the following specifications, and the novel features of the device will be particularly pointed out in the appended claims.

My invention is illustrated in the accompanying drawings forming part of this application, in which—

Figure 1 is a view in side elevation, of a portion of a wheel flange, showing the oil distributor applied thereto.

Fig. 2 is a view in front elevation, of the wheel flange oil distributor.

Fig. 3 is a side plan view of the oil distributor shoe, showing a cavity extending longitudinally therein by dotted lines.

Fig. 4 is a sectional view of a portion of a wheel flange, and a top plan view of the oil distributor shoe, showing the longitudinal cavity and oil pipe by dotted lines.

Fig. 5 is a top plan view of a tapered locking key.

Fig. 6 is a section on the line B—B of Fig. 4.

In carrying out my invention I have provided a bracket or attaching bar 2, which is made of such material and dimensions as will permit of its being attached to the frame of a car truck by means of a bolt 3, or any similar form of attachment. In the end of the bar 2 adjacent the oil distributor, is a counter-sunk hole or eye 5, from which is suspended a hanger 6, bearing in its lower end a comparatively large opening or loop 7, adapted to have detachably secured therein the reduced end 8 of the distributor shoe 9. Said detachable means employs a counter-caved groove 10, which receives the lower side of the loop 7, and a tapered locking key 11 inserted in the space above the tapered side 12 of the reduced end of the shoe, as shown in Fig. 1. Means for holding the key 11 in its respective position is provided by the spring 13, which has its central portion passed over the attaching bar 2 and the portions on each side of the center being wound around their respective spring bosses 35 or lugs 4 and 4^a, having the ends extended over their respective grooves 14 and 14^a. The spring 13 is also adapted for the further purpose of holding the distributor end 15 of the shoe 9 in contact with a revolving wheel flange, as shown in Fig. 1.

Referring now to the construction of the distributor shoe 9, which may be of any suitable material but preferably of cast steel, it is provided with an oblong cavity 16 (shown by dotted lines in Figs. 3 and 4), having relatively proportioned walls 17, 18, 19 and 20, so as to equalize the normal wear of the distributor shoe end 15 when the same is engaged with a revolving wheel flange. This cavity having properly proportioned walls serves as a source of least resistance which the wearing action of a revolving wheel flange will follow. Thus it is seen that by constructing the walls as shown in Fig. 6, the shoe will submit to a continued feeding-up action against the wheel flange. The wall 18 being the thickest of the walls, is

subjected to the tread of the wheel as well as to the tread side of the flange, thereby receiving the most wear, while the opposite wall 17 is subjected only to the opposite side 5 of the flange and receiving lateral wear only. It will be seen that the walls 19 and 20 will give way to a wearing action of the wheel flange fully as fast as the wall 18 will permit them to feed-up. Thus a continued 10 feeding-up of fresh material to compensate for the lateral wearing action within the shoe end 15 is accomplished, thereby maintaining a comparatively snug fit over the wheel flange. A pipe 21 extends parallel 15 with and partially within the wall 18, having its discharge opening 23 in position for engaging the tread side of the wheel flange 1, while its end opposite 22 projects through the reduced end 8 forming a nipple to which 20 a hose or other flexible tube may be attached.

It should be understood that the distributor shoe may be constructed in pairs of right and left, for discharging oil to the 25 thread side of a wheel flange of either the right or left wheel of a car truck.

From the foregoing description of the various parts of the device, the operation thereof may be readily understood.

30 A lubricating fluid is supplied to the distributor, by means of attaching a hose or other flexible tube to the nipple 22. The bar 2 is bent so as to conform itself to being attached to the frame of a car truck 35 for holding the device in position to lubricate the flanges thereof. When in its normal position the spring 13 holds the distributor shoe in its attachment with its hanger by means of the tapered locking key 40 11, and simultaneously holds the distributor shoe in contact with the wheel flange. When it becomes necessary to renew the distributor shoe, the ends of the spring 13 may be lifted 45 out of their respective grooves 14 and 14^a and the key 11 driven out of the loop 7, thus releasing the shoe preparatory to a new one being applied.

It is obvious that various modifications are within the scope and spirit of this invention, and I do not limit myself to the 50 specific construction shown.

Having thus described my invention, what I claim as new and desire to secure by Letters Patent is:

55 1. In a flange oiling device, an oil distributor detachably secured to a hanger, a locking key for locking said detachable connection, a spring for holding the locking key in position and acting to hold the oil 60 swab in contact with a wheel flange.

2. In a flange oiling device, an oil distributor detachably secured to a hanger, a locking key for locking said detachable connection, a spring for holding the locking key in position and acting to hold the oil 65

swab in contact with a wheel flange, a pipe within the oil swab arranged to discharge oil on the tread side of a wheel flange.

3. In a flange oiling device, an oil distributor detachably secured to a hanger, a 70 locking key for locking said detachable connection, a spring for holding the locking key in position and acting to hold the oil swab in contact with a wheel flange, a pipe within the oil swab arranged to discharge oil on the tread side of a wheel flange, and 75 walls comprising the oil swab adapted to compensate for lateral wear on the inner surface of the oil swab.

4. In a flange oiling device, an oil distributor shoe, provided with a longitudinal cavity having one thick and three comparatively thinner walls, a pipe extending parallel with and partially within the thick wall, having its discharge end within the 85 distributor shoe and the end opposite forming a nipple.

5. In a flange oiling device, an oil distributor shoe, having a reduced end tapered on one side, a groove on the opposite side, 90 a longitudinal cavity in the distributor shoe open to the wheel flange, having one thick and three comparatively thinner walls, a pipe extending parallel with and partially within the said thick wall, having its discharge end within the distributor shoe, and the end opposite projecting out of the reduced end of the shoe forming a nipple.

6. In a flange oiling device, in combination, a supporting bar, an eye in the end of the supporting bar, a hanger suspended from the eye, spring bosses on each side of the eye near the end of the said supporting bar, a distributor shoe detachably secured to the said hanger, and a spring carried 100 by the said spring bosses adapted for securing said detachable connection and acting to hold the discharge end of the distributor shoe in contact with a revolving 105 wheel flange.

7. In a flange oiling device, in combination, a supporting bar, a counter-sunk hole in the end of the supporting bar, spring bosses on either side of the counter-sunk hole, a hanger suspended from the counter-sunk hole, a loop in the end of the hanger, an oil distributor shoe detachably secured in the loop, a locking key for locking said detachable connection, a spring carried by the spring bosses for holding the locking key in position and acting to hold the discharge end of the distributor shoe in contact with a wheel flange, a pipe within the distributor shoe arranged to discharge oil on the tread side of a wheel flange.

8. In a flange oiling device, in combination, a supporting bar, a tapered opening in the end of the supporting bar, a hanger suspended from the tapered opening, a loop in the end of the hanger, an oil distributor

shoe detachably secured in the loop, a locking key for locking said detachable connection, a spring carried by the spring bosses for holding the locking key in position and acting to hold the discharge end of the distributor shoe in contact with a wheel flange, a pipe within the distributor shoe in contact with the tread side of a wheel flange, and walls comprising the distributor shoe adapted to compensate for wear on the inner surface of the same.

9. In a flange oiling device, in combination, a supporting bar, a pair of spring bosses near the end of the supporting bar, an opening between the spring bosses, a hanger suspended from the opening, a loop in the end of the hanger, an oil distributor shoe detachably secured in the loop, a locking key for locking said detachable connection, a spring for holding the locking key in its position, and acting to maintain the

oil distributor shoe in contact with a wheel flange, said distributor shoe comprising an oblong extension having an end adapted to a wheel flange, and the opposite end reduced to fit into the said loop, a groove extending across the lower side of the reduced end, a tapering side opposite to the groove, a longitudinal cavity in the distributor shoe open to the wheel flange, having one thick and three comparatively thinner walls, a pipe extending parallel with and partially within the thick wall, a discharge opening in the pipe arranged to discharge oil on the tread side of a wheel flange, an end of the pipe extending through the reduced end of the distributor shoe forming a nipple for attaching a tube.

In testimony whereof I affix my signature on this 30th day of January, 1918.

CHARLES F. HOOFER.
